STENCIL PRINTING APPARATUS

Harmon P. Elliott, Watertown, Mass., assignor to
The Elliott Addressing Machine Company, a
corporation of Massachusetts

Application March 28, 1933, Serial No. 663,128

5 Claims. (Cl. 101—49)

This invention relates to stencil printing apparatus of the general character shown in my Patent No. 1,909,910 dated May 16, 1933, and comprises certain modifications thereof and improvements thereon.

The main object of the present invention is to produce a base unit for the type of apparatus shown in said prior application which shall be in the simplest and cheapest form capable of printing addresses from a series of stencils, or of skipping those not then to be used, while allowing the operator to inspect each stencil before it enters the printing zone to then determine his choice of the possible operations therewith, but which simple base unit may have quickly fastened thereto any one of a variety of attachments which, when in operation, will severally enable it to do many other things in the stencil printing line.

Thus another object of the invention is to produce a set of attachments which will do the work of the invention of another of my pending applications Ser. No. 639,171, filed October 24, 1932, and which may be easily clamped as a unit on to one end of the base unit and thereupon, with no modification of the latter other than the installation of the proper ink bearing platen sector, enable the completed apparatus to print names, etc. in column formation on a sheet or slip of paper fed through the printing zone under control of said attachment.

A third object of the present invention is to provide a message printing attachment for said base unit which shall be easily inserted therein and be practically noiseless in operation, and which when so installed will enable the so completed apparatus to print a message, an advertising design, or any other desired subject matter upon one side of each of a series of postcards or sheets of paper upon which names and addresses have been, or may be, printed by the base unit alone.

A fourth object of the present invention is to provide a simple apparatus which may be mounted on said base unit and thereupon cause the so completed apparatus to print repeatedly from any one of a series of address bearing stencils so that the name and address cut in said stencil may be printed at several places upon a sheet of paper or envelope or wrapper.

A fifth object of the invention is to provide an adjustable stencil magazine and similarly adjustable stencil receiver so that these may be arranged either to handle the ordinary small stencil used in my system or the larger stencil

having an extension frame on one side, on which extension classifying marks may be made, and also handle either of these stencils in a manner which will cause the printed legend to be either right side up or upside down, when viewed from the position of the operator, the stencil feeding mechanism of the base unit being similarly adjustable to handle either of such stencils in either of the manners described.

Other minor objects of the invention will be obvious to those skilled in the art from the subjoined detail description of the construction and of the mode of operation of the apparatus shown in the drawings.

The best form of apparatus embodying my invention at present known to me is illustrated in the accompanying eight sheets of drawings in which

Fig. 1 is a side elevation with the inking unit removed and certain parts broken away.

Fig. 2 is a plan view of the same character.

Fig. 3 is a partial plan view with parts broken away and others shown in section, the message printing attachments being shown in operative position.

Fig. 4 is a partial vertical section on the line 4—4 of Fig. 3, with parts broken away, and

Fig. 5 is a cross section of the same character taken on line 5—5 of Fig. 3.

Fig. 6 is a detail, axial section of the air cushion for the message stencil carrier, shown on an enlarged scale.

Fig. 7 is a partial plan view with parts broken away and others shown in section illustrating the arrangement of the stencil magazine for handling small sized stencils.

Fig. 8 is an enlarged detail cross section on line 8—8 of Fig. 7 showing the detachable drive connection for the upper sector and the cooperation of the stencil with the rotating sectors.

Fig. 9 is a partial plan view with parts broken away and others shown in section illustrating the attachment for producing repeat printing from any desired stencil, and

Fig. 10 is a cross section on line 10—10 of Fig. 9, and

Fig. 11 is a detail longitudinal section on line 11—11 of Fig. 9.

Fig. 12 is a detail plan view with parts broken away and others shown in section, the guide used when feeding cards by hand to the address printing apparatus being shown in operative position and

Fig. 13 is a perspective view of said guide.

Fig. 14 is a rear elevation of the machine with parts broken away, and others shown in section,

illustrating the sheet feeding and printing mechanism.

Fig. 15 is a plan view of the same with parts broken away and others shown in section, and

Fig. 16 is a detail plan view of the stencil reservoir or collector in a position the reverse of that shown in Fig. 2.

Throughout the drawings like reference characters indicate like parts. Much of the apparatus here shown is substantially the same as that of my above noted Patent No. 1,909,910, or pending application Ser. No. 639,171, filed Oct. 24, 1932, and therefore need not be described in detail. The base unit comprises a supporting frame 51 on which are journaled two rotating platen sectors connected together by gearing mounted in housing 61, and indicated in broken lines at 6 in Fig. 1, so as to rotate in opposite directions when actuated by hand crank 1 mounted on shaft 2, also journaled in housing 61, and to which the upper platen sector 103 (Fig. 2) or other upper sector 3 or 203 is releasably clutched so that it can be readily taken off said shaft and another platen sector of different area of face substituted for it.

4 (Fig. 1) is a portion of the usual ink applying roll of an inking mechanism for distributing an even layer of ink over the curved surface of the upper platen sector 3, 103, or 203, whichever may be in use. This roll is a part of a floating inking unit (not shown) pivoted on the shaft 7 supported in a housing 141 carried by the main frame, the construction being similar to that of the inking apparatus shown and described in a second Patent No. 1,922,533, granted to me Aug. 15, 1933.

The stencils 50 for use with the ink impression mechanism are stacked in magazine 61 with the major dimensions of their stencil panels parallel to the shaft 2 so that they can be fed sideways between the platen sectors along the oppositely grooved guides 8 and 99.

The base unit briefly above described, when combined with stencils of proper shapes, may be used as a simple addressing apparatus, the post cards or envelopes to be addressed being fed in by hand as indicated at 110 in Fig. 12, correct registration of the printed matter being assured by the guide 48 which is adjustably mounted on table 66 by means of setscrew 49 engaging a slot in a rear extension of said guide. With the use of various other attachments hereinafter described, however, said simple base unit may be modified to print a series of names or other legends in column formation on a sheet of paper, or to print a uniform message or design on a series of postcards or other articles, or to print any desired number of repetitions of the same name and address, or other short legend, using either the small stencil 100 as shown in Figs. 7, 9, and 11, or stencils 50 having a frame extension 115 (Fig. 2) on which memoranda may be written. Also these large stencils may be fed to the printing zone with the stencil panel leading, as shown in Fig. 2, so that any identifying marks on frame extension 115 may be read by the operator as the same appear between the magazine 61 and the rotating sectors 103 and 5, or with the frame extension leading, as shown in Fig. 15, if it is desired to reverse the stencils and print the addresses upside down, for any reason.

The sheet feeding attachment is shown in Figs. 14 and 15, and the stencil feeding apparatus is there shown as adjusted to handle the large stencils 50 so as to feed them to the printing zone

with their frame extensions 115 leading, though small stencils 100 could be used by partially collapsing the magazine 61. In either case the stencil should be thus reversed because the printing of the list should begin at the top of the sheet, and that end of the sheet must be fed first to the printing zone so that, as looked at by the operator who stands near the operating crank, the printing will be upside down.

The sheet handling attachment is practically the same as that described in my above mentioned prior application Ser. No. 639,171, except that it is more easily removable and can be taken out or put back as a unit. It comprises a sheet supporting plate 10 which serves as an extension 15 of the table top 66 of the main frame 51, and preferably is supported in this position by means of the thumbscrew 70 passing through a hole in the brace 68 and screwing into the side of main frame 51. A clamp is provided for holding the rear end of a sheet of paper 13 in such position on the plate 10 and table top 66 that the forward end of said sheet will project into the open space 26 between the rotating platens when the latter are not in contact one with another. Consequently when said sectors have thereafter rotated sufficiently to cause them to bite on the forward end of sheet 13, the latter will be pulled to the right a short distance, and, if a stencil is at the same time inserted between said sectors, the legend cut in said stencil will be printed on said sheet. The sheet-holding clamp, as here shown, comprises the housing 11 sliding on plate 10 and rack rod 14, which latter extends along one side edge of plate 10 and is revoluble in perforated lugs 15, 15, carried by the long bar 116 which is fastened to the depending flange 117 on said plate 10. A long coiled tension spring 16, one end of which is connected at 17 to the clamp housing 11, passes around the loose pulley 18 journaled at the outer end of bar 116 and has its other end anchored to said bar at 19. The tension of spring 16 normally tends to pull housing 11 back against the lefthand lug 15 near the outer end of rack rod 14, unless said clamp housing is held in some advanced position by reason of the loose pawl 21, carried in the housing 23, engaging one of the teeth 22 on the rack rod 14.

The arc of the curved face of the ink bearing platen sector 3 (used for sheet feeding) is sufficiently long to give an initial step-by-step feed to the sheet 13 considerably in excess of the net feed movement necessary to space the lines of printing on said sheet, and a lost motion mechanism is incorporated in the pawl and ratchet holding device so that the pawl 21 will be dragged over only one tooth on the rack rod 14 during each printing operation. When the sectors release the sheet after such printing, clamp 11, holding the sheet, is pulled back by spring 16 against said pawl. This lost motion effect is obtained by loosely confining the pawl slug 21 in housing 23 which has two perforated heads 24 and 25 through which rack rod 14 extends. The endwise play of housing 23 over pawl slug 21 is slightly less than the difference between the length of the arc of the curved face of sector 3 and the distance by which the teeth 22 are spaced apart. When the sheet 13 is not under tension, spring 16 pulls pawl bearing housing 23 back so that its right hand head 25 rests against the right hand end of the pawl slug 21, as shown in Fig. 14. When the sectors grasp sheet 13 and pull it to the right, looking at Fig. 14, the clamp and the pawl housing 23 move with it. The first

portion of said movement takes up the lost motion space between the rear end of pawl slug 21 and the rear housing head 24. Thereafter the final movement of the sheet carries pawl 21 with it. This will move the pawl 21 along rack rod 14 a distance slightly in excess of that between two adjacent ratchet teeth 22 formed in the upper portion of the surface of said rod, and consequently, when the platen sectors release the sheet, the spring 16 will promptly pull it and pawl 21 backward and so cause the pawl to engage the next one of the ratchet teeth behind it, and thereby leave said sheet in an advanced position such that at the next revolution of the platen 15 sectors the line of printing produced by the next card stencil on said sheet will be spaced, by a predetermined distance, below the legend next before printed.

The details of construction of the preferred form of paper clamp as illustrated in Figs. 14 and 15 comprise a vertically swinging bar 27 pivoted at one end to housing 11 at 28, and having the upper surface of its other end slightly inclined downwardly and outwardly to cooperate with the horizontally swinging latch 30 pivoted to the housing at 31. Bar 27 swings close to the vertically projecting ledge or flange 32 formed on housing 11 so that when the bar is swung down on the rear end of sheet of paper 13 and latched in the position shown in Figs. 14 and 15, said sheet is firmly attached to housing 11. An overhanging lug 33, carried by housing 11 and under which latch 30 may be swung, assists in holding said latch down firmly on bar 27. If said bar is given a slight curvature so that its free end is slightly raised from plate 10 when free, but is bent downward when latch 30 slides over its inclined upper edge, a very firm grip of the clamp on the paper 13 is assured. The details of this construction are shown in my above mentioned co-pending application Ser. No. 639,171. 34 is a short projecting handle forming the rear end of latch 30 by means of which it may be swung into and out of operative position. 45 The stencil magazine indicated generally at 61 is capable of adjustment so as to hold either the large stencils 50 or the small stencils 100, and similarly the stencil feeding apparatus, which comprises the slide 41 movable in the grooved stencil guides 9 and 99, is adjustable so as to cooperate with either the small stencils or the large stencils, and also to cooperate with the large stencils 50 either when their extension frames 115 extend toward the slide 41, as shown in Fig. 2, or are in the reverse position, as shown in Fig. 15.

The stencil feed slide or pusher 41, as best shown in Fig. 2, is provided with a pivot housing 40 clamped to it by the setscrew 140 and provided with pins 44, 44, which engage perforations in slide 41. In the position shown in Fig. 2, the slide 41 is adjusted to feed the large stencils 50 for address printing with their frame extensions 115 to the rear, and yet have the stencil panel portion in proper position to cooperate with the rotating sectors and to leave the markings on frame extensions 115 visible before the printing operation is performed. When it is desired to feed the large stencils in the reverse position the housing 40 is shifted so that the setscrew and the pins 44 will engage another set of holes 42 in slide 41. In this position, also, the small stencils 100 can best be fed to the printing zone by the slide 41, the width of said small sten-

cil frame being just one half that of the large stencils.

As it is desirable that the stencils shall always lie in the magazine 61 with their index notches 114 on the side of the magazine which carries the single upright 64, the said magazine should be reversed when it is desired to feed the large stencils with the frame extensions 115 in advance, and this can be done by taking out the setscrews 65, 65, which hold the two magazine sections 62 and 64 to the stencil guides 9 and 99. At the same time the stencil magazine obviously must be moved closer to the printing zone, as otherwise the frame extensions 115 would lie in the printing zone during the printing operation, instead of the stencil panels occupying that position. Accordingly another set of holes 72, 72 are provided in the stencil guides 9 and 99, as shown in Figs. 2 and 3, with which the setscrews 65 may engage when the magazine is reversed and moved into the position shown in Figs. 14 and 15. When the magazine is in the position shown in Fig. 1 the setscrews 65 engage the holes 71, 71, shown in Fig. 3. When the small stencils 100 are being used and the stencil magazine parts are in the position shown in Fig. 7, the half section 64 of the magazine carrying the single upright is held in position by its setscrews 65, 65, engaging the pair of holes 73, 73, shown in Fig. 3. The two upright members 62, 62, forming one half of the magazine 61, are held together by a rib 63 (see Fig. 15).

The stencil feed slide 41 is reciprocated in the manner shown in my Patent No. 1,588,099, dated June 8, 1926, i. e. by means of the adjustable connecting rod 39, pivoted at one end to the housing 40 and provided at the other end with a hook 45 for engaging the crank pin section 38 (Fig. 3) of the hand crank 4. When said hand crank is rotated in the direction of the arrow shown in Fig. 1 slide 41 will be reciprocated, if the connecting rod is raised as shown in full lines in Fig. 1 so that the hook 45 engages the crank pin section 38, being yieldingly held in that position by the pin 119, yieldingly forced toward the inside of the hook by the spring 120. If, however, it is desired to repeat printing of the legend on any one of the stencils 50 or 100, the stencil feed slide 41 may be disabled by forcing the connecting rod 39 down into the broken line position shown in Fig. 1, whereupon the crank pin section 38 will be freed from engagement with hook 45 and the sectors can be rotated by turning crank 4, but without feeding any more stencils forward, in the manner described in my Patent No. 1,563,268, granted Nov. 24, 1925.

In order to retain in operative position the stencil then in the printing zone during a repeat printing cycle I prefer to employ the attachment shown in Figs. 9, 10, and 11, which comprises a plate 101 adapted to slide on the upper surface of the stencil guides 9 and 99, being guided thereon by its downwardly turned ends 102, 102, and a finger 103 carried by said plate and projecting downward into the space between the stencil guides in a position to engage the front edge of the stencil then located between the rotating sectors, as best shown in Fig. 11. Tension springs 104, anchored to the stencil guides at 105 and connected to plate 101, normally pull it to the right (looking at Figs. 9 and 11) but yield as the stencil 100 there shown is forced to the left by the rotating sectors during the printing operation. As soon as said sectors let go of the stencil after each printing operation the springs 104 pull

the plate 101 and finger 108 to the right, thereby returning the stencil 100 to the initial position for another printing operation. To disable this stencil return apparatus, when desired, finger 108 is mounted on a shaft 107 journalled on plate 101 in lugs 106, 106, and provided at its outer end with the knurled head 109. By rotating the head 109 with the fingers in a counterclockwise direction (looking at Fig. 11) the finger 108 will be swung up and over into the broken line position above plate 101 in Fig. 11, so that stencils can then be fed consecutively beneath the plate 101 while it is left in position waiting for the appearance of another stencil, the name and address cut in which is to be repeated: whereupon the finger 108 may be rotated down into operative, full line position, and the above described procedure of repeat printing gone through with again. The operation would be the same if large stencils 59 were being used.

If, on the other hand, it is desired to skip printing from any particular stencil, the spring pressed pin 46 mounted in crank 1 may be pulled out into broken line position shown in Fig. 2, with the result that its inner end will then no longer engage the hole provided for it in crank flange 41 (Figs. 1, 2, 3 and 7) which is fast on the driving shaft 2, the hand crank 1 being loosely journalled on said shaft. When the hand crank 1 is pinned to the crank flange 41, the sector 5 will be rotated through the action of gearing 6, and the upper sector 103 mounted on shaft 2 for address printing will also be caused to rotate therewith by reason of the radial pin 112 in shaft 2 (see Fig. 8) engaging the notch 113 in the end of sleeve 37 which carries whatever upper sector is in use. When, however, the pin 46 is withdrawn from engagement with crank flange 41, the hand crank 1 may rotate idly without rotating the sectors and if the connecting rod 39 is then in raised, full line position, the slide 41 will feed a stencil or stencils through the printing zone without any printing being done therefrom. The cam lugs 43, 43, on the upper surface of slide 41 lift the stack of stencils slightly at each reciprocation of said slide, and then let them fall again, thus preventing their getting jammed in the magazine and not feeding down to the slide.

The sector-carrying sleeve 37 is provided with an outer knurled head 137a by which it may be pulled off of shaft 2, and another sleeve, and sector carried thereby, substituted for it. Three types of upper, ink bearing sectors are required. The sector 3 with a short arc of ink-carrying face shown in Figs. 8, 14, and 15 does the single line printing in cooperation with the sheet feeding attachment. The sector 103 with the medium length of arc of ink carrying surface shown in Figs. 2, 7, 9, and 12 cooperates with the entire operative surface of the panel of the stencils 50 or 100 to print the names and addresses, while the sector 203 with the very long arc of ink carrying surface shown in Figs. 3 and 4 cooperates with the message bearing stencil 60 to print the message or other matter on the side of the postcard opposite that on which an address has been or will be printed, or on sheets of paper, if desired. The same lower platen sector, or anvil 5, cooperates with all three of these upper sectors.

The large flexible message stencil 60 (Figs. 3 and 4) is mounted in a sheet metal frame 59, substantially such as is described in my before mentioned Patent 1,909,910. This frame is gripped between sectors 5 and 203 and intermittently pulled to the left (Figs. 3 and 4) be-

tween them for printing operations. A new and improved apparatus is here shown, however, for pulling back the carrier and stencil between printing operations. The mechanism for doing this shown in said prior Patent 1,909,910 was rather noisy in operation, and, after much experimentation, I have devised the air-cushioned device shown in Figs. 3 to 6 which is practically noiseless. A spring, or springs such as 97, 97, pull the carrier 59 back to initial position as before, but instead of then slamming up against a fixed stop, as in the prior construction, the piston 94, connected by rod 95, 96, to frame 59 and moving in cylinder 93, closed at its outer end, forms an air cushion which noiselessly checks the return movement of the message stencil. The air trapped in cylinder 93 can only escape through small leakage port 87 (Fig. 6) as the piston is forced toward said port, and when this return movement of the stencil and piston 20 is nearly completed, valve 89 carried by the piston practically closes that port. Consequently the remaining portion of the movement of piston 94 is very slow, and finally stop member 98 comes quietly to rest against pad 88 in the cylinder end. Cylinder 93 is fast on cross strip 90, clamped at one end to stencil guide 99 by setscrew 91 and steadied at its other end by pin 92 engaging a hole in guide 9. Springs 97, 97, are anchored to this strap, so that the whole 30 stencil apparatus for message stencil printing can be removed as a unit by backing off setscrew 91, lifting strap 99 and pulling carrier 59 out through the cutaway portions 9a and 99a of the upper walls of the grooves in the stencil guides 9 and 99 (shown in Fig. 2). These guides are supported by brackets 74 and 75, clamped to main frame 51 by screws 76.

For simplicity and cost saving no automatic feeding apparatus for the postcards (such as is shown in my Patent 1,909,910) is employed with the present invention. For address printing the cards are fed by hand as shown in Fig. 12. This can be easily done because the stencil panels run crossways of the guides 9 and 99, so that the lines of printing also run that way and the postcards or envelopes can be pushed in endways from the side of the stencil runway, as indicated in Fig. 12, leaving one end of the card projecting far enough beyond stencil guide 99 to be retained in 50 the grasp of the operator's thumb and forefinger, while the middle of the card is in the printing zone. When the message is to be printed, however, this cannot be done because then the stencil lines of lettering run parallel to guides 9 and 99. 55 Therefore I provide the card holder indicated generally at 53 in Figs. 3 and 4 for handling the postcard during the message printing operation. This holder has side and end flanges 55, and a spring clip 58 for holding a card 110 when slipped 60 under it. The holder is pivoted by a thumb screw 54 to stencil guide 99 and is normally swung out by spring 55, anchored at 69, into the full line position shown in Fig. 3. A projecting handle and stop 57 enables the operator to swing 65 the holder and contained card into the broken line position shown in Fig. 3, in which position the card 110 is in registry with the stencil 60, the forward ends of both projecting into the open 70 space 26 existing between the cutaway portions of rotary sectors 5 and 203 just before they are rotated into the position shown in Fig. 4, and ready to be grasped by the latter when so rotated. When grasped, the card is pulled out from 75

under spring clip 58 and away from side flanges 56, so that when the operator lets go of handle 57 spring 55 will swing the holder back into full line position, ready to receive another postcard.

- 5 Repeat printing of a name and address or of other matter may also be done while still using the stencil-carrying frame 59 by cutting the lines of printed matter crossways in a large flexible stencil 60 and feeding the envelopes (if it is desired to print a return address thereon), or the cards or sheets, by hand,—if the operator does not wish to use either the card-holder last above described or the repeat attachment shown in Figs. 9, 10, and 11, or has neither at hand. Cards and envelopes can then conveniently be fed by hand because they can be slid under the stencil guides with their longer dimensions extending at right angles thereto. The use of this expedient results in a saving of first cost to the user by enabling him to do practically all the hereinbefore described varieties of work without buying the special repeat attachment or the card holder.

25 The special form of adjustable and reversible stencil receptacle, indicated generally at 8, is located at the left hand end of the base unit, as shown in Figs. 1 and 2. As there shown it is expanded to receive the large stencils 50 and arranged to receive them when they are being delivered to it in the normal position shown in Fig. 2.

30 The same receiver is shown in Figs. 7 and 9 in a collapsed position ready to hold the small stencils 100 when delivered to it in the normal position, with notches 114 in their rear edges. In Fig. 16 the parts are shown in a transition stage of adjustment between the arrangement for holding the large stencils and that for holding the small stencils, and ready (when adjusted as to size) to receive either in reversed position, i. e. with the notch 114 in the advancing edge.

35 It should be noted that in the present invention the stencil magazine is divided along a line at right angles to the stencil guides 9 and 99 each section thereof forming a bridge across said guides and that these divided parts are movable along said guides, which are fixed in position, to accommodate stencils of different dimensions lengthwise of the guides, while in my hereinbefore mentioned Patent 1,909,910 the two parts of the divided magazine were permanently mounted on the separate stencil guides and only moved toward or from one another with said guides, which were adjustable to carry stencils of different widths.

40 I prefer to employ stencils having the double frames and interleaved strip of tougher material 121 (see Fig. 8) with which the platen sectors can cooperate in feeding the stencils, all as explained in my Reissue Patent No. 18,151, dated Aug. 18, 1931. In the present case the sectors grasp this strengthening welt 121 at the ends of the stencils instead of along the sides thereof, as was the case in the apparatus shown in my 45 said reissue patent, the upper sector 3 or 103 being used.

45 All these stencils are provided with a notch 114 in the edge which will be uppermost when the stencils are held so that they can be read, and in order to ensure that these notches shall always come uppermost when the stencil stacks are placed in filing trays it is desirable to have the stencils always deposited in the receiver 8 with the notches 114 adjacent to the single upright 164. The reason for this is that the trans-

5 fer tray (not shown) picks up the stencils by being slid up along that side of the stencil receiver, in the act of transferring the stack of stencils from the receiver to the filing tray or to magazine 61, and also slides down that side of magazine 61 when depositing the stack therein. For this reason the stencil receiver should be reversible as well as the stencil magazine 61. To this end the stencil receiver is supported (as best shown in Figs. 1 and 2) from the tubular sleeves 83 which can be slid on and off the supporting pins 82, projecting from the main frame 51 at the ends of stencil guides 9 and 99, and be reversed before their return to operative position. The sleeves 83 are connected together by 10 the cross bar 84 from which the depending, trough-shaped member 162 is supported. From the lower end of this member, which forms one side of the stencil receiver, extends horizontally the bottom flange 129, in which is mounted a set-screw 81 cooperating with a slot in a base extension member 77, the free end of which supports the single upright 164 forming the other side of the stencil receiver. On vertical rod 85, also depending from cross bar 84, there slides the 25 sleeve member 86 carrying the finger 186 which projects through a vertical slot 187 in the member 162 and supports the plate 29 to which is pivoted at 78 the swinging plate 79. Tension spring 35, anchored to cross bar 84, yieldingly 30 supports the finger 186, the plates 29 and 79 and whatever stack of stencils rest on the latter two. As the weight of the stack increases by the addition of stencils, the spring 35 is expanded correspondingly so that the top of the stack of stencils is always slightly below the plane of the 35 grooves in the guides 9 and 99.

As the result of the above described construction the stencil receiver 8 can be collapsed to the condition shown in Figs. 7 and 9 by loosening the thumbscrew 81 and sliding the member 77 along the surface of the bottom plate 129 after the pivoted plate 79 has been swung around into the position shown in these figures of drawings. This leaves the single upright 164 spaced away 45 from the trough member 162, forming the other side of the receiver, only half the distance at which it formerly was spaced, and consequently the small sized stencils 100 are snugly held in the receiver and can be removed therefrom by pulling the transfer holder (not shown) up along the exterior of the single upright 164, after the receiver has been pulled off the pins 82, 82. The main frame 51, with the usual four supporting legs therefor, is properly balanced on said four 50 legs when the sheet feeding attachment is fastened thereto. When the latter is removed, however, the stencil receiver 8 when filled with stencils may tip the machine over toward that end. Therefore I have provided a fifth leg 52, 60 as shown in Fig. 1, to prevent this.

55 Friction clips on the stencil guides 9 and 99 for preventing the stencils from being kicked outward from the printing zone by any too rapid revolution of the platen sector, are shown at 12, 65 12 (Figs. 1 and 2).

60 It will be seen that the hereinbefore described apparatus differs from that disclosed in my before mentioned Patent 1,909,910, in that the stencil guides 9 and 99 are not adjustable to and from one another and this is rendered possible by the fact that the address bearing stencils are here fed sidewise along the guides, the length of such stencils being equal to the width of the message stencil carrier 59, so that both can be 75

handled by the fixed set of guides. This feeding of the stencils sidewise through the printing zone also enables the base unit to print lines in column formation on a sheet of paper, as in the 5 manner disclosed in my other prior application 639,171, but in the apparatus shown in such last mentioned application the adjustability of the stencil guides had to be retained because the stencils were there fed endwise through the 10 printing zone in the addressing operation. A serious objection to that arrangement, however, is, as before suggested, that when the postcards or envelopes are fed by hand into the printing zone for printing with stencils in that position, 15 it is extremely difficult for the operator to retain his grasp on them, as they practically disappear under the stencil guides by the time they have reached proper position for printing. The feeding of the stencils sidewise through the printing 20 zone has, in the present invention, besides simplifying the structure of the machine, overcome this difficulty because each card or envelope can now be pushed in endwise from the side of the printing zone (as shown in Fig. 12) and there is 25 always enough of the end of it projecting when in printing position to enable the operator to retain a firm grasp on it. The same difficulty, however, crops up when one comes to the message printing operation, and to overcome this I 30 supply the card holder 53 shown in Fig. 3, the functions of which have been hereinabove explained. Also this improvement avoids any 35 necessity for placing the stencil guides 9 and 99 above the level of a plane tangent to the lower sector 5, and the consequent flexing downward of the stencil during the printing operation.

An important commercial advantage of the invention arises from the fact that it is embodied in a built-up structure which can be varied by 40 changing the various attachments to the base unit so as to develop a multi-printing machine capable of performing all of the standard operations with card stencils,—one class at a time,—or the base unit, which is simply a hand operated addressing apparatus of the simplest form, may 45 be sold at a low price for this work alone, and thereafter, as the purchaser may wish to extend his field of operations, he can buy, one at a time, each for a price within his reach, the 50 message printing attachment, the sheet feeding attachment, and/or the repeat printing attachment.

The spacing between the stencil magazine and the printing zone is such that when the large 55 stencils are used, arranged as shown in Fig. 2, the frame extension 115 on each stencil is clearly 60 visible between the magazine and the platen sectors, as the stencil panel approaches the printing zone. Consequently any desired system of sales memoranda can be maintained on these 65 frame extensions and the operator thereby advised, as each stencil comes to printing position, whether he should print from it or skip it. If he desires to skip it he turns the hand crank 1 70 backward far enough to bring the crank flange 47, pinned to it, to a bearing on the hinged stop 122 (Figs. 1 and 2), which makes it certain that the cutaway portions of the two sectors 5 and 103 are opposite one another, leaving an open 75 space 26 through which a stencil or stencils may freely pass. Then on pulling out the pin 46 the backward rotation of the hand crank may be continued while the crank flange 47 and sectors remain at rest. This pushes the stencil which has reached printing position, onward through

the open space 26 without the performance of any printing operation and, upon the completion of this rotation of the hand crank 1, the spring pressed pin 46 will ride up on the cam surface of the flange 47 and drop into the hole provided for it in said crank flange, thus putting the parts in position for a resumption of clockwise rotation of the crank 1 and the resulting revolution of the platen sectors, causing consecutive printing of addresses. The hinged stop 122 yields and lifts 10 as the crank flange 47 comes under it once in each clockwise rotation of the hand-crank, but will not permit a counterclockwise rotation of said flange. 15

If the operator desires to repeat the printing 15 of any one of the names and addresses he turns the finger 108 down into the position shown in Figs. 10 and 11, and disables the stencil feed mechanism by pushing down on the connecting rod 39, thereby disabling the stencil feed mechanism. Clockwise rotation of the hand crank then rotates the platen sectors without feeding any new stencils to them. 20

Having thus printed the various names and 25 addresses on a series of postcards, the message 30 or advertising matter can then be printed upon opposite sides of said postcards by pulling off the upper sector 103 and replacing it with the platen sector 203, taking off the stencil magazine 61, 35 pulling out the stencil feed slide 41 with its connecting rod 39, and installing the message stencil carrier mechanism and the postcard holder 53, as shown in Figs. 3 and 4. Thereupon the message printing is done by the operator inserting the postcard 110 into the holder 53, as indicated in Fig. 3, pushing the holder into the printing zone until the combined stop and handle 57 comes to a bearing against the stencil guide 99, as there shown in broken lines, and then rotating the hand crank 1 with the pin 46 engaging the 40 crank flange 47. This pulls the message stencil carrier 59 and the contained message stencil 60, together with the underlying postcard 110, between the rotating sectors, thus printing the message upon the postcard. Toward the end of each 45 revolution of the sectors they let go of the stencil carrier 59, which is thereupon snapped back into its initial position by springs 97, 91, but, the latter portion of this backward movement being checked by the air-cushion mechanism previously 50 described, the carrier 59 comes to rest without creating shock or noise. At the same time the printed postcard drops on the table 65 or into any 55 shallow receptacle placed there to receive it. After this printing operation has been so far initiated that the postcard is firmly grasped by the sectors, the operator can let go of the handle 57 and thereupon, after the rear end of the postcard has been freed from the holder 53, the spring 59 will snap said holder back into the full line 60 position shown in Fig. 3, ready to receive another postcard for the next printing operation. 65

When the operator wishes to make up a payroll or similar document requiring the listing of 70 names in a column, the stencil magazine 61 is 65 put back, but in a reversed position as shown in Fig. 15, so that the stencils placed therein, whether large or small, will be fed along the guides 9 and 99 with the letters of the legends cut therein upside down, as viewed by the operator. The stencil feed slide 41 is also put back in operative position and the sheet handling attachment, which is a self-contained unit, is fastened to the base unit by the setscrew 70. Thereupon the bottom edge of the sheet to be printed 75

is clamped to the housing 11 by means of the clamping bar 27 in such position that when the said clamp is pulled back against the lefthand lug 15, the upper end of said sheet will project into the printing zone far enough so that the first printing operation will be performed at the desired point on the sheet. The ink bearing sector 3 is then installed and, on rotation of the hand crank 1, the sheet 13 will be intermittently pulled forward through the printing zone, as line after line of matter is printed thereon from successive stencils.

After any desired amount of such printing has been done, rack rod 14 can be partially rotated by lifting up weighted crank-handle 36 (Fig. 14), thereby moving teeth 22 out of line with pawl 21; whereupon spring 16 will pull the clamp housing 11 and sheet 13 back to starting position. Thereupon said sheet can be conveniently freed from the clamp, if desired. When crank-handle 36 is released, it drops back to substantially vertical position, thereby automatically returning teeth 22 to normal position for again cooperating with pawl 21 whenever printing is resumed.

Various changes in the details of the apparatus here shown and hereinbefore described can, of course, be made without departing from the substance of my invention so long as the general arrangement and mode of operation hereinbefore explained are preserved, in whole or in substantial part, and the resulting modified structure is within the definitions of the appended claims.

Having described my invention, I claim:

1. In a printing apparatus having a base unit comprising a supporting frame, a pair of revoluble platen sectors journaled thereon, the upper one of which has an ink carrying surface, means for guiding a series of stencils consecutively between said sectors in position such that the lines of matter to be printed which are cut in said stencil will be parallel to the axes about which said sectors revolve, and mechanism for progressively feeding said stencil along said guiding means toward and between said platen sectors the combination, with said above described apparatus, of a unit structure capable of being easily attached to or detached from said base unit and comprising means for yieldingly holding a sheet of paper

beneath said guiding means with the free end thereof projecting between said platen sectors; whereby, as said platen sectors are revolved said sheet will be intermittently pulled along between them and the legends cut in said stencils thereby printed on said sheet in column formation. 5

2. In an apparatus such as defined in claim 1 in which the supporting frame of said base unit has an upper plane surface substantially parallel to said guiding means, and in which the detachable unit has a setscrew for attaching it to one end of said frame and a plate forming an extension of the said upper plane surface of said main frame when fastened thereto by said setscrew. 10

3. A printing apparatus employing stencils 15 comprising, in combination, a pair of parallel, oppositely grooved fixed stencil guides spaced apart far enough to permit a stencil to be slid along their grooves with the longer dimension of its stencil panel extending transversely of said guides, a pair of oppositely revoluble platen sectors between which stencils sliding in said guides may pass, a reciprocable stencil pusher mounted on said guides, and means for synchronously rotating said sectors and reciprocating said pusher, 25 the latter being adjustable toward and from said sectors; whereby stencils having frames of different sizes and shapes can be used at different times by correspondingly varying the field of movement of said pusher. 30

4. An apparatus such as defined in claim 3 combined with a stencil magazine mounted on said guides and also adjustable toward and from said sectors.

5. In a printing apparatus employing stencil 35 cards comprising a pair of oppositely grooved guides along which such stencils are slid to a printing zone, a magazine for such stencils composed of two complementary sections each of which is bridged across, and adjustably mounted 40 on, said guides; whereby such two-part magazine, having a line of division between said complementary sections extending across said guides, may be expanded or contracted according to the dimensions of the contained stencils extending 45 lengthwise of the guides.

HARMON P. ELLIOTT.
